UNITED STATES PATENT OFFICE.

ELIAS H. NABHAN, OF LAWRENCE, MASSACHUSETTS.

PICKER-STICK.

971,625.

Specification of Letters Patent.

Patented Oct. 4, 1910.

Application filed March 25, 1910. Serial No. 551,467.

To all whom it may concern:

Be it known that I, ELIAS H. NABHAN, a citizen of the United States, residing at Lawrence, in the county of Essex and State 5 of Massachusetts, have invented certain new and useful Improvements in Picker-Sticks, of which the following is a specification.

My invention relates to the picker sticks of looms.

10 It comprises a combination of parts to replace the sweep strap and power strap now commonly used. It is well known that on account of the continual blows which the picker stick gives to the shuttle caused by the action of the sweep stick and sweep arm on the picker stick, the wear on all the parts is very severe. All these parts wear out and break very rapidly. This breakage not only causes increased expense but requires that the loom should be stopped until 20 repairs are made. On account of this severe hammering, ordinary frictional adjustments of the parts are not satisfactory as they are not permanent. It is also desirable that the 25 wooden parts, especially the picker stick should be weakened as little as possible by boring holes therein.

My invention comprises a combined sweep strap and power strap. All the parts in 30 which strength is desirable are made of metal, but where the sweep strap comes in contact with the picker stick, leather padding is used.

In the drawings, Figure 1 is a back view 35 of my device. Fig. 2 is a side view. Fig. 3 is a top view, part of the sweep strap being broken away to show the construction. Fig. 4 is a detail from the side of the sweep strap showing the adjusting washer. Fig. 5 40 shows the sweep strap without the adjusting washer.

A represents a picker stick of the usual construction.

B represents the sweep stick through 45 which the forward motion is given to the picker stick. The picker stick and sweep stick are of the usual construction.

The sweep strap C is made of a single strip 10 of metal bent in the form of a U 50 and preferably made of spring steel. Near the ends and opposite each other are longitudinal slots 11. Inside steel strip 10, and preferably glued thereto is a leather strip 12 which conforms to the inner shape of strip 10. Leather strip 12 is pierced with 55 slots which adjoin slots 11. Inside the loop

of strips 10 and 12, I provide a cushion which consists of strips of leather 13 set edgewise, glued and closely packed together. This cushion 13 is also held together and in 60 place by a rivet 14 which passes entirely through strips 10, 12 and 13 as shown by the dotted lines in Fig. 3.

The sweep stick B near its end has a bolt hole 16. Through slots 11 and the hole 16, 65 I pass a bolt 20 by which the sweep strap C is attached to sweep stick B. A nut 21 on bolt 20 serves to hold the parts together.

If it is desired to use the sweep stick and sweep strap at their extreme length, the 70 sweep strap is pulled out until bolt 20 passes through the extreme end of slots 11 as shown in Fig. 5. Nut 21 is screwed up and the parts are thus firmly held in place.

For the purpose of adjusting the parts, 75 that is, of lengthening or shortening the sweep strap, I provide adjusting washers E. These washers are somewhat longer and wider than slots 11 and each has an elongated boss 30 which just fits inside of a 80 slot 11, and extends through both steel strip 10 and leather 12. Through this washer E and boss 30, at a little distance from the center, I bore a bolt hole 31 of a size to permit the passage of the shank of bolt 20. 85 Referring to Fig. 4, it will be readily seen that by pushing boss 30 into slot 11 in the position shown in Figs. 3 and 4, sweep strap C will be shortened to some extent. If it is desirable still further to shorten it, the 90 nut 21 is loosened and both washers E are reversed. This brings the hole 31 to the position shown by the dotted lines in Fig. 2, whereby the sweep strap is still further shortened. It is evident that a number of 95 washers with holes in different positions may be kept on hand to allow any desired adjustment. At the back of the loop of sweep strap C, I rivet or otherwise attach a strip of metal 17 which passes up and 100 back over cushion 13 and terminates in an open hook 18.

To support sweep strap C, in place of a power strap, I use an adjustable supporting member which consists of a strip of metal 105 F. This strip F is a little narrower than the back of picker stick A and at its bottom terminates in an open hook 40. Strip F near its bottom has a longitudinal slot 41 and near its top a longitudinal row of pin 110 holes 42. Through slot 41 passes a round headed screw 43 into the back of picker

stick A. At a distance about equal to the length of slot 41 above screw 43, I drive a pin or headless screw 44. This pin 44 is of a size to just enter any one of holes 42. A link 5 H which is shown as provided with a loop at each end, one passed over hook 40 and the other passed over hook 18, connects strip F with sweep strap C and supports sweep strap C upon picker stick A.

10 If it is desired to change the position of sweep strap C as for instance to raise it, it is necessary only to slightly loosen screw 43 enough to allow strip F to be pulled out clear of pin 44 as shown by the dotted lines in Fig. 2. Strip F can then be pushed up or down and any desired hole 42 may be pushed over pin 44. Screw 43 is then tightened and the device is thus locked in place.

15 What I claim as my invention and desire 20 to cover by Letters Patent is:

1. In a loom, the combination of a picker stick, with a sweep strap which comprises a U shaped strip of spring steel with a lining 25 of leather and a cushion of leather inside the loop together with oppositely disposed slots near the ends of the loop, adjusting washers each of which has a boss which enters a slot in the sweep strap and has a passage which is off the center of the boss, 30 together with a sweep stick through which is a hole, bolts which pass through the passages in the washers and said sweep stick hole, and means for positively supporting and adjusting the sweep strap on the picker 35 stick as described.

2. In a loom, the combination of a picker stick, with a sweep strap which comprises a

U shaped strip of spring steel with a lining of leather and a cushion of leather inside the loop together with oppositely disposed slots near the ends of the loop and a hook at the top, adjusting washers each of which has a boss which enters a slot in the sweep strap and has a passage which is off the center of the boss, together with a sweep stick through which is a hole, bolts which pass through the passages in the washers and said sweep stick hole, a metallic supporting strip which terminates at the bottom in a hook and has a longitudinal slot at the bottom and a plurality of pin holes at the top, with a screw which passes through the slot and into the picker stick, a pin in the picker stick which enters a pin hole, and a metallic link which connects the supporting strip hook with the sweep strap hook.

3. In a loom, the combination of a picker stick, with a sweep strap which comprises a U shaped strip of spring steel having oppositely disposed slots near the ends, adjusting washers each of which has a boss which enters a slot in the sweep strap and has a passage which is off the center of the boss, together with a sweep stick through which is a hole, and a bolt which passes through the passages in the washers and said sweep stick hole.

In testimony whereof I, hereto affix my signature in presence of two witnesses.

ELIAS H. NABHAN.
